UNITED STATES PATENT OFFICE.

LEON L. SIBLEY, OF MONROE BRIDGE, MASSACHUSETTS.

MEANS FOR FASTENING ROLLS TO SHAFTS.

1,281,861.

Specification of Letters Patent. Patented Oct. 15, 1918.

Application filed March 6, 1918. Serial No. 220,779.

To all whom it may concern:

Be it known that I, LEON L. SIBLEY, a citizen of the United States, residing at Monroe Bridge, in the county of Franklin 5 and State of Massachusetts, have invented certain new and useful Improvements in Means for Fastening Rolls to shafts, of which the following is a specification, reference being had to the accompanying drawings.

This invention relates to certain improvements in means for fastening rolls to shafts and has relation more particularly to a device of this general character for securing 15 a mill roll of paper to the rewinding shaft or the like and it is an object of the invention to provide a novel and improved means whereby a roll of paper may be effectively held by a re-winding shaft or the like without injury of the web.

It is also an object of the invention to provide a novel and improved means of this general character including a collar surrounding the shaft and adapted to extend 25 within an end portion of the bore of the roll together with means for expanding the outer end portion of the collar for frictionally engaging the roll.

Another object of the invention is to provide a novel and improved means for fastening a roll paper or the like to a shaft including a collar surrounding the shaft and adapted to extend within the bore of the 30 paper roll together with an expanding member coacting with an end portion of the collar for causing said end portion of the collar to frictionally engage the roll and wherein the shaft is provided with means for forcing the expanding member inwardly 35 of the collar.

A still further object of the invention is to provide a novel and improved means of this type including an expandable collar surrounding the sleeve together with an expanding member movable longitudinally of the shaft and movable inwardly of the collar to expand the same and a member carried by the shaft for forcing the expanding member inwardly of the collar together 45 with means operating automatically to impart outward movement to the expanding member when the forcing member is moved away from the collar.

The invention consists in the details of 50 construction and in the combination and arrangement of the several parts of my im-

proved means for fastening rolls to shafts whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the 65 better understood, I will now proceed to describe the same with reference to the accompanying drawings, wherein:

Figure 1 is a view in elevation illustrating a means for fastening a roll to a shaft constructed in accordance with an embodiment 70 of my invention; and

Fig. 2 is a longitudinal sectional view taken through the structure as disclosed in Fig. 1 with a shaft and certain of the parts 75 in elevation.

As disclosed in the accompanying drawings 1 denotes a threaded mill roll shaft provided with a longitudinally disposed groove or channel 2. The shaft 1 is adapted to be 80 disposed through the bore of a mill roll of paper and especially of a roll to be slotted.

Coacting with the opposite end portions of the bore of the roll are the collars C surrounding the shaft 1 and movable longitudinally thereof. The inner ends of the collars C extend within the opposite end portions of the bore of the roll and contact one with the other while the outer end portions of the bore of each of the collars is 90 enlarged and said collar throughout the extent of said enlarged or counter-bore is slotted so that said outer portion of the collar may be expanded to frictionally engage the roll so that the roll may be effectively secured to the shaft. Coacting with the outer 95 or slotted end portions of each of the rolls is an expanding member M tubular in form and slidably mounted upon the shaft 1. The inner end portion of the member M is 100 adapted to extend within the outer end portion of the coacting collar C and at a predetermined point intermediate its length the expanding member M is provided with the beveled shoulder or annular cam 3 which 105 serves to expand the slotted end portion of the collar C when the member M is forced inwardly thereof. Threaded upon the shaft 1 and coacting with the outer end of each of the members M is a nut N which may be 110 readily turned by hand and which affords an effective means for imparting movement

105
110

to the member M inwardly of the coacting collar C in order to effect the desired expansion of the outer end portion of the collar C. It is also preferred that the collar C have 5 an inwardly directed pin 7 or the like extending within the groove 2 so that the collar is held against rotation around the shaft 1 whereby the expanding of the outer end portion of said collar C is materially facilitated.

10 The collars C, members M and nuts N are properly positioned upon the shaft 1 after the shaft has been disposed through the bore of the mill roll and, as is believed to be 15 clearly apparent to those skilled in the art to which my present invention appertains, these elements may be readily positioned irrespective of the width of the web comprised in the roll.

20 In order to facilitate the outward movement of the expanding member M relative to its coacting collar C when a nut N engageable with the member M is moved in a direction away from the collar C, I provide the 25 expandible member 5 seated within the enlarged portion or counter-bore 6 of the collar C and which is compressed by the member M when said member is forced inwardly of the collar C. As herein disclosed the ex- 30 pansible member 5 comprises a coil spring encircling the shaft 1.

From the foregoing description, it is thought to be obvious that a means for fastening rolls to shafts constructed in accordance with my invention is particularly well adapted for use by reason of the convenience and facility with which it may be assembled and operated and it will also be obvious that my invention is susceptible of 35 some change and modification without departing from the principles and spirit there- 40

of and for this reason I do not wish to be understood as limiting myself to the precise arrangement and formation of the several parts herein shown in carrying out my invention in practice except as hereinafter claimed. 45

I claim:

In combination with a shaft insertible through the bore of a paper roll, a pair of 50 collars loosely surrounding said shaft and adapted to extend within the bore of the paper roll through opposite ends thereof, the inner ends of said collars contacting, the outer portions of the collars being slotted 55 whereby the same may be expanded and the outer end portion of the bore of each of said collars being enlarged, members loosely surrounding the shaft and extending within the slotted end portions of the collars to expand 60 the same, a coil spring within the enlarged portion of the bore of each of the collars and surrounding the shaft, said spring being interposed between the inner end of the member and the inner end of the enlarged portion of the bore of the collar for automatically moving the member away from the collar, members mounted upon the shaft outwardly of the first members and contacting with said first named members to force 65 the same inwardly of the collars to expand the outer end portions of the collars and for placing the spring under tension, and means carried by each of the collars coacting with the shaft for holding the same 70 against rotation about the shaft. 75

In testimony whereof I hereunto affix my signature in the presence of two witnesses.

LEON L. SIBLEY.
